BENJAMIN REBOURG, OF DENAIN, FRANCE, ASSIGNOR TO SOCIÉTÉ FRANÇAISE DE CONSTRUCTIONS MÉCANIQUES (ANCIENS ÉTABLISSEMENTS CAIL), OF DENAIN, FRANCE.

CARBURETER.

977,044.

Specification of Letters Patent. Patented Nov. 29, 1910.

Application filed April 26, 1910. Serial No. 557,765.

To all whom it may concern:

Be it known that I, BENJAMIN REBOURG, civil engineer, citizen of France, residing at Denain, Nord, in the Republic of France, have invented new and useful Improvements in Carbureters, of which the following is a specification.

This invention relates to a carbureter of the general type described in my pending application (Serial Number 474,210 filed Jan. 26, 1909) and more particularly to the device by means of which the expansible annular part is actuated so as to vary the sectional area of the passage through the restricted portion of the same while operating at the same time the sliding tube controlling the flow of the combustible liquid through the sprayer tube.

My invention consists in actuating said expansible annular part by rotating its movable end which I preferably obtain by means of a rack meshing with teeth provided on the outer periphery of said movable end, the rack being actuated either by means of a piston, a speed regulator or by hand.

By the particular arrangement of the strips forming the expansible part, the rotation of the movable end of said part has for its effect to move the same axially with regard to the fixed end of said part which results in varying the sectional area of the restricted portion of the same and also the number of the orifices in the sprayer tube left free by the outer sliding tube connected to said movable end. The above described manner of operating the expansible part has the advantage of necessitating only a small power for operating the expansible part so that the same responds exactly to the actuating means (piston, regulator or hand) whereby the inflow of explosive mixture is accurately regulated while the proportion of air and combustible remains exactly the same.

In the annexed drawing: Figure 1 is a vertical section through a carbureter according to my invention, the rack being connected to a piston operated through the depression caused by the aspiration from the engine, the carbureter being shown in its normal position in which the flow of explosive mixture is minimum. Fig. 2 is a section similar to Fig. 1, the flow of explosive mixture being maximum. Fig. 3 is a section along the line 3-3, in Fig. 2. Figs.

4 and 5 show the expansible annular part on a larger scale, in elevation and cross section along the line 5-5, Fig. 4, respectively.

The combustible liquid contained in the constant level tank 1 is led to the sprayer 2 consisting of a tube closed at its upper end below which it is provided with a number of small holes situated at various levels. A tube 3 fits the sprayer tube 2 closely and is capable of sliding up and down thereon so as to cover according to its vertical position a greater or less number of the holes in the sprayer 2. Air is admitted into the carbureter as indicated at 4 through an expansible annular part or sleeve 5 in the form somewhat of a hyperboloid, composed of thin elastic strips bent and arranged helically so as to overlap each other, the constricted part of the sleeve being approximately on a level with the small holes of the sprayer.

The lower end of the expansible annular part or sleeve 5 is fixed at its lower end to the body 6 of the carbureter and it is held at its upper end between a ring 7 and a nut 8 by which the upper part of the sleeve is guided in the carbureter body. The ring 7 has radially extending arms and a central hub in which the tube 3 is supported. Said ring 7 is provided in its outer periphery with teeth 9 and a cylindrical rack 10 which is adapted to slide in the carbureter body meshes with said teeth. The rack 10 is provided at its end with a piston or diaphragm 11 which is acted upon by a spring 12. The casing 17 of the carbureter in which said diaphragm is located is divided thereby in two chambers 13, 14, the first of which communicates through an opening 15 with the part connected to the engine cylinder, while the other chamber 14 communicates with the atmosphere.

Normally the diaphragm 11 is forced outward by the spring 12 as shown in dotted lines in Fig. 3 in which position the ring 7 and the upper part of the expanding sleeve 5 are turned in the direction of the inclination of the strips so that the constricted part of the sleeve 5 has a minimum diameter (Fig. 1).

When the engine is working and according to the speed which is regulated through the valve 16, the depression caused by the aspiration of the cylinder and transmitted through the opening 15 on to the piston 11

- permits the atmospheric pressure of compressing the spring 12 and thereby sliding the rack 10. The ring 7 is then rotated by said rack together with the upper part of the sleeve in the direction of the arrow (Fig. 3) the rotation being assisted by the flexibility of the sleeve. It results therefrom that the sectional area of the passage through the constricted part of the sleeve is increased and a greater amount of air is sucked in by the engine. At the same time, the ring 7 is lifted with the tube 3 which opens a greater number of holes in the sprayer, whereby the flow of explosive mixture is increased while the proportion of combustible and air remains the same as the respective amounts of the same increase with the same ratio and the velocity of air around the sprayer is substantially the same.
- 20 When the flow of explosive mixture is maximum the parts are in the position shown in full lines in Figs. 2 and 3. If the depression decreases, the reverse movements take place under the action of the spring 12.
- 25 When the depression caused by the engine increases or decreases, the rack 10 is then moved in one direction or in the reverse direction, respectively so that the flow of the explosive mixture is accurately regulated
- 30 while the proportion of air and combustible remains exactly the same.
- Having now described my invention, what I claim as new and desire to secure by Letters Patent is:
- 35 1. A carbureter comprising in combination: a constant level tank, a sprayer having orifices situated at various levels, a tube sliding over the sprayer and adapted to cover

more or less the orifices in the latter, an expandible annular part having a constricted passage for the air approximately on the level of the orifice in the sprayer, and having its lower end secured to the carbureter body, and its upper end connected to the tube sliding over the sprayer, and means for rotating the upper end of said part, substantially as described and for the purpose set forth.

2. A carbureter comprising in combination: a constant level tank, a sprayer having orifices situated at various levels, a tube sliding over the sprayer and adapted to cover more or less the orifices in the latter, an expandible annular part having a constricted passage for the air approximately on the level of the orifices in the sprayer, and having its lower end secured to the carbureter body, and its upper end connected to the tube sliding over the sprayer, teeth on said upper end, a rack engaging with said teeth, a piston on said rack, a closed chamber in which said piston can move in and out an orifice in the wall of the chamber affording communication between one face of the piston and the suction of the engine, means for admitting the air to the other face of the piston and a spring adapted to force the piston against the air pressure, substantially as described and for the purpose set forth.

In testimony whereof I have signed my name to this specification in the presence of two subscribing witnesses.
